(57) **CLAIM**

The ornamental design for a solar cell, as shown and described.

DESCRIPTION

FIG. 1 is a top perspective view of a solar cell showing our new design;

FIG. 2 is a top plan view thereof;

FIG. 3 is a front elevation view thereof;

FIG. 4 is a rear elevation view thereof;

FIG. 5 is a right side elevation view thereof, the left side elevation view being a mirror image of FIG. 5; and,

FIG. 6 is a bottom plan view thereof.

1 Claim, 3 Drawing Sheets

FIG. 1

FIG. 2

FIG. 5

FIG. 6
